FLUID COMPRESSOR

Nicolas Herzmark, Paris, France

Application November 14, 1931, Serial No. 575,099
In Great Britain November 18, 1930

11 Claims. (Cl. 230—172)

This invention has reference to fluid compressors of the kind comprising a cylinder mounted in a casing with a compressor-piston adapted to be reciprocated in the cylinder, and is more particularly intended for compressing air to be stored in containers for operating engine turning gear on automobiles, but capable also of use for tire inflating, paint spraying and other purposes.

One object of the present invention is to maintain the piston of the compressor in a rectilinear path so as to prevent undue friction and wear in the cylinder. Other objects of the invention are to provide a high speed compressor, to prevent the undue heating of the cylinder head, to provide a pre-compression of the fluid to be compressed, to eliminate the dead space at the head of the cylinder by means of an oil layer, to allow the piston to work idly when the pressure in the container has reached a predetermined degree and to lubricate the piston in the cylinder in a particular manner.

According to the present invention, the piston of the compressor on its non-working stroke in the cylinder causes a pre-compression of fluid in a chamber in prolongation of the cylinder, this pre-compressed fluid being caused to enter the cylinder before the commencement of the working stroke of the piston within the cylinder. Oil from the chamber is carried with the pre-compressed air into the cylinder and forms a seal or layer around the head of the cylinder to eliminate dead space and to cool the head of the cylinder. The piston is provided with a cross-head frame-member of a transverse length greater than the stroke of the piston, and travelling in guides within the compressor casing, so that the reciprocating movements of the piston in its cylinder are steadied by the cross-head frame-member. Said arrangement makes it possible to provide a certain play between the piston and the cylinder, while allowing said piston to always remain concentric with said cylinder. Fluid tightness is obtained by means of the oil which is maintained on the piston by the grooves provided in the latter. The cylinder is mounted in the compressor casing in such a manner that its lower end depends into a chamber in the interior of the casing and such dependent portion is provided with oppositely arranged ports level with the top of the piston when the latter is at the bottom of its stroke, these ports communicating with the chamber in the casing. The pre-compressed fluid passes from the chamber to the cylinder through these ports when the latter are uncovered. The head of the cylinder is provided

with a valve which when open delivers to a container for the compressed fluid, so that such fluid compressed in the cylinder during the upward movement of the piston, will be forced through the valve to the container; this valve is so constructed that when the back pressure in the container is sufficiently great, the valve will be put out of action.

The invention is hereafter described with reference to the accompanying drawings, in which:

Figs. 1 and 2 are sectional elevations, at right angles to one another, of an air compressor suitable for a compressed air starter for an explosion engine.

Figure 3 is a section on the line A—B of Fig. 1 and Fig. 4 is a plan view of the compressor represented in Fig. 2.

Fig. 5 is a detail view in section, upon a larger scale.

The casing *a* of the compressor comprises a sump portion *b*, and air chamber *c* and a head portion *d*. It is provided also with an air inlet valve *e*, a cylinder *f* dependent from the head *d* into the air chamber *c* and with suitable ball or similar bearings *g* for a driving crankshaft *h* having a crank pin *h*¹. Figs. 2 and 4 show the casing *a* provided with end plates carrying the shaft bearings, detachably secured upon the central portion by bolts and nuts *a*¹. The air chamber *c* is provided with parallel guiding face plates *c*¹ *c*² secured on the inner wall of the casing *a* by screws *c*³.

In the head *f* of the cylinder *f* is arranged a delivery valve shown in the form of a ball *i*, said ball being mounted in a hollow mushroom valve *j* held to its seating *j*¹ in the head of the cylinder by a spring *j*² which bears against a washer *j*³ secured by a cotter on the upper end of the hollow valve stem *j*. An adjustable stop pin *i*¹ is arranged above the ball *i* to limit the lift of the latter.

The cylinder *f* is formed with ports *f*² *f*³ located exactly above the level of the top of the piston *k* when the piston is at the lower end of its stroke (see Fig. 1), in which position these ports allow communication between the air chamber *c* and the interior of the cylinder *f*.

When the ball is lifted from its seat in the valve *j* by the pressure of air compressed in the cylinder *f*, the air passes through the center of the valve head to the interior of the hollow stem *j* and thence by a suitable passage *i*² and pipe *i*³ to a container *i*⁴. When however the mushroom valve *j* is moved from its seating *j*¹ as hereafter explained, the air contained in cylinder *f* and forced

up by the piston *k* will pass by the seating *j*¹ (and not pass the ball *i*), thus circulating idly through a passage *d*¹ leading to a channel *d*² which delivers back to the air chamber *c*.

5   Mounted upon the crank pin *h*¹ by means of a bush or die *k*⁰ with sliding engagement, is a cross-head *k*¹ forming part of the piston *k* but of a transverse length considerably greater than the stroke of the piston *k*. This cross-head *k*¹ is shown secured by studs *k*² to a U-shaped frame-member *k*³, the outer walls of which bear against the parallel face plates *c*¹ *c*², and the lower part of which engages slidingly with the bottom of the bush or die *k*⁰ on the crankshaft.

10   As the piston *k* rises and falls, due to the motion of the bush or die on the rotating crankshaft *h*, the frame-member *k*³ is guided by the plates *c*¹ *c*² so that the piston *k* is steadied and kept in a truly rectilinear path.

15   The lower part of the frame-member *k*³ is also provided with a dipper *k*⁴ which enters a well or recess *b*¹ in the sump *b*. This dipper *k*⁴ is provided with an annular flanged or similar foot *k*⁵, which serves to splash up the oil collected in the well *b*¹.

20   The head portion *d* of the casing *a* is shown provided with a detachable cap *d*³ screwed upon a ferrule itself screwed into said head portion, to allow of the fitting of the cylinder *f* in place, the cylinder being retained by means of its outward flange *f*³ resting on a shoulder *d*⁴ in the head, and of the valves *i* and *j* with their accessories, and also to allow of subsequent access to these parts.

25   The sump *b* being filled with relatively thick oil, for example, castor oil, the rotation of the crank pin *h*¹ will cause the piston *k* and cross-head frame-member *k*¹ *k*³ to reciprocate together, moving respectively in the cylinder *f* and 30 between the guiding face plates *c*¹ *c*². As the crank pin rotates, the bush *k*⁰ moves from side to side of the frame-member *k*³ which it will be noted is bathed with oil; by this construction, a clearance space may be provided between piston *k* and cylinder *f* without the piston ceasing, 35 in its rectilinear displacement, to be concentric with said cylinder. Fluid tightness is insured by the oil, which is not given time enough to flow out due to the braking action produced by grooves *j*⁴.

40   As the piston *k* rises, it forces compressed air past the ball valve *i* and through the port *i*² into the container *i*⁴. When the piston descends, it allows the valve *i* to close and creates a fall in pressure in the cylinder *f* sufficient to produce a 45 suction on the valve *j* strong enough to draw the mushroom head thereof away from seat *j*¹, thereby permitting the idle circulation of air into the passages *d*¹ and *d*² and back to the air chamber *c*, as hereinbefore suggested. This suction action continues during the major portion 50 of the down stroke, and in fact until the piston reaches the level of the ports *f*² *f*². As the piston rises, the suction produced in the chamber *c* draws in air through the valve *e*; this air is subjected to a preliminary compression in the chamber *c* during the return movement of the piston by reason of the fact that (as will be noted from Figs. 2 and 3) the capacity of the free annular space in the chamber *c* is relatively small as compared with the displacement in the piston *k*. There is thus provided a decrease in volume and a corresponding increase in pressure of the air previously admitted to the chamber *c* through the valve *e*. Also, on the downward stroke, valve 65 *e* is closed by reason of this increased pressure in

the chamber *c*. The continued downward movement of the piston *k* finally uncovers the ports *f*² *f*² whereupon the partial vacuum is relieved by a rush of air from the chamber *c* into the cylinder. At the same time, the descent of the frame-member *k*³ into the lower part of the air chamber *c* displaces the air upwardly. This air, which has been slightly pre-compressed in the chamber *c*, is subsequently compressed to the full extent by the upward movement of the piston, 10 during which the supply of air in the chamber *c* is replenished through valve *e*. Meanwhile the dipper *k*⁴ has entered the well or recess *b*¹ in the sump and has splashed up the oil, which, as the operation continues, not only maintains the 15 lubrication of the crank pin *h*¹, cross-head frame-member *k*¹ *k*³ and piston *k*, but impregnates the air in the chamber *c* so that oil passes with the air through the ports *f*² *f*² into the cylinder above the piston. The upper or head end of 20 the cylinder is so designed as to eliminate as much as possible any dead space or clearance and such dead space is filled with oil by the action of the piston *k*. In this way there is provided and maintained a film of oil deposited around the 25 valve *j* at the position of highest air pressure in the cylinder *f*, with the result that the head of the cylinder is kept comparatively cool, while the compressed air forced into the container also loses heat by expansion. 30

The pipe *i*³ delivers to the container *i*⁴ below the level of a bath of oil *i*⁵ in said container so that the oil is subjected to the pressure of compressed air stored in the container. When the pressure above the oil reaches a predetermined 35 degree, oil is forced back along the pipe *i*³ to passage *i*² and to the interior of the head *d* where it bears upon the upper end of the mushroom valve *j*; when the oil pressure is sufficient to overcome the valve spring *j*², it forces the valve *j* off its seat *j*¹ so that the piston no longer passes air through the ball valve *i*. Any air driven forward by the piston will pass through the valve seating *j*¹ into the passage *d*¹; along channel *d*² back to the 40 chamber *c*. 45

The channel *d*² is shown closed at top by a screw plug *d*⁵ for manufacturing purposes; the sump *b* can be filled up with oil by removing the inlet valve *e*. A lateral passage *d*⁶ from the interior of the head *d* and parallel with passage *d*¹ 50 communicates with the channel *d*² by way of a needle valve *d*⁷ which can be screwed back to allow the return of superfluous oil from the interior of the cap *d*³ to the sump *b*, and also to replenish the sump by returning surplus oil from the container. 55

In order to insure a proper air tight seal between the piston *k* and the wall of the cylinder without the use of piston rings, the piston is grooved as shown in Fig. 5. A peripheral gutter *f*⁴ is formed with an inwardly curved wall *f*⁵ above the gutter to catch any oil which may leak from the top of the piston down between the piston and cylinder wall and such oil owing to its viscosity and noncompressible nature is scraped off the wall by the gutter *f*⁴ to form upstanding beads as at *f*⁶, which spread outwardly during movement of the piston and seal the joint. Four of these gutters *f*⁴ are indicated in Fig. 1. 60

The amount of oil splashed up from the sump *b* by the dipper *k*⁴ can be regulated by altering the diameter of the foot *k*⁵ of the dipper. This foot may be reduced in diameter or made adjustable in any manner desired. 70

Although described and shown in its applica- 75

tion to an air compressor for a storage tank in connection with an engine turning device operated by compressed air, this improved compressor, which is capable of a high speed of operation, can obviously be applied to other purposes.

While I have disclosed what I deem to be preferred embodiments of my invention, I do not wish to be limited thereto, as there may be changes 10 made in the construction, form and disposition of the parts without departing from the principle of my invention as comprehended within the scope of the appended claims.

What I claim is:

15 1. A fluid compressor of the type described, comprising in combination, a casing, a cylinder in said casing, a piston adapted to reciprocate in said cylinder, driving means for actuating said piston, a chamber in line with said cylinder, means operatively connected to said driving means for precompressing air in said chamber prior to final compression thereof in said cylinder, said cylinder being provided with ports connected with said chamber and opening into said cylinder 20 25 in such a position as to be uncovered by said piston at the end of the non-working stroke thereof.

2. A fluid compressor of the type described, comprising in combination, a casing, a vertical cylinder in said casing, a piston adapted to reciprocate in said cylinder, driving means for actuating said piston, a chamber in said casing located below said cylinder in line therewith and adapted to contain said driving means and the outer 30 35 part of the piston, whereby air is precompressed in said chamber during the downward stroke of the piston, said cylinder being provided with ports connected with said chamber and opening into said cylinder at points level with the top of said 40 piston when the latter is at the bottom of its stroke, the lower end of said chamber being adapted to contain oil, means operatively connected with said driving means for splashing said oil, whereby oil from the chamber is carried 45 with the precompressed air through said ports into said cylinder and forms a seal or layer around the head of the cylinder to eliminate dead space and to cool the head of said cylinder, means for admitting air into said chamber during the upward stroke of said piston, a receiver for the compressed air, and means for allowing air to flow from said cylinder into said receiver during the upward stroke of said piston.

3. A fluid compressor of the type described, comprising in combination, a casing, a vertical cylinder in said casing, a piston adapted to reciprocate in said cylinder, a chamber in said casing located below said cylinder and in line therewith, two vertical parallel guiding plates in said chamber placed at a distance from one another substantially greater than the stroke of the piston, a cross-head frame-member rigidly connected to said piston and adapted to slide between said guiding plates, driving means for actuating said cross-head, whereby air is precompressed in said chamber during the downward stroke of the piston, said cylinder being provided with ports connected with said chamber and opening into said cylinder at points level with the top of said piston when the latter is at the bottom of its stroke, the lower end of said chamber being adapted to contain oil, means for admitting air into said chamber during the upward stroke of said piston, a receiver for the compressed air, and means for allowing air to flow from said cylinder into said

receiver during the upward stroke of said piston.

4. A fluid compressor of the type described, comprising in combination, a casing, a vertical cylinder in said casing, a piston adapted to reciprocate in said cylinder, a chamber in said casing located below said cylinder and in line therewith, two vertical parallel guiding plates in said chamber placed at a distance from one another substantially greater than the stroke of the piston, a cross-head frame-member rigidly connected to 10 said piston and adapted to slide between said guiding plates, driving means for actuating said cross-head, whereby air is precompressed in said chamber during the downward stroke of the piston, said cylinder being provided with ports connected with said chamber and opening into said cylinder at points level with the top of said piston when the latter is at the bottom of its stroke, the lower end of said chamber being adapted to contain oil, means operatively connected with said 15 driving means for splashing said oil, whereby oil from the chamber is carried with the precompressed air through said ports into said cylinder and forms a seal or layer around the head of the cylinder to eliminate dead space and to cool 20 the head of said cylinder, means for admitting air into said chamber during the upward stroke of said piston, a receiver for the compressed air, and means for allowing air to flow from said cylinder into said receiver during the upward 25 stroke of the piston.

5. A fluid compressor of the type described, comprising in combination, a casing, a vertical cylinder in said casing, a piston adapted to reciprocate in said cylinder, a chamber in said casing 30 located below said cylinder in line therewith, the lower end of said cylinder depending into said chamber, driving means for reciprocating said piston in said cylinder located in said chamber, whereby air is precompressed in said chamber during the downward stroke of the piston, the lower part of said cylinder which projects into said chamber being provided with ports opening into said cylinder at points level with the top of said cylinder when the latter is at the bottom of its 35 downward stroke, a spring seated valve opening in the inward direction for connecting said chamber with the atmosphere whereby air is admitted into said chamber during the upward stroke of said piston, a receiver for the compressed air, and a valve at the upper end of said cylinder for allowing air to flow from said cylinder into said receiver during the upward stroke of said piston.

6. A fluid compressor according to claim 5 in which the lower part of said chamber is adapted 55 to contain oil, further comprising means operatively connected to said driving means for splashing said oil in the said chamber, whereby oil from said chamber is carried with the precompressed air through said ports into said cylinder and forms a seal or layer around the head of the cylinder so as to eliminate dead space and to cool 60 the head of said cylinder.

7. A fluid compressor according to claim 3, in which the means for admitting air into said chamber consists of a spring seated valve opening inwardly, and the means for allowing air to flow from said cylinder to said receiver consists of a valve, further comprising means operative by the back pressure in said receiver, adapted to directly connect the upper end of said cylinder with said chamber when said back pressure exceeds a predetermined value.

8. A fluid compressor according to claim 3, in which the means for allowing air to flow from said 75

cylinder to said receiver, comprise, a valve seat provided in the inner face of the cylinder head, a mushroom valve adapted to cooperate with said seat, a conduit for connecting the inner face of said valve with the chamber, a stem on said valve extending throughout the cylinder head, said stem being provided with a longitudinal conduit extending throughout its length, a ball valve disposed in the last mentioned conduit so as to allow the air to flow outwardly and to prevent it from flowing inwardly, and a spring for operating said mushroom valve on its seat.

9. A fluid compressor according to claim 3, further comprising an oil chamber located above said cylinder head, and a pipe for connecting said oil chamber to said receiver, in which a certain quantity of oil is present at the bottom of said receiver, the means for allowing air to flow from said cylinder to said receiver comprising, a valve seat provided in the inner face of the cylinder head, a mushroom valve adapted to cooperate with said seat, a conduit for connecting said valve seat with the air chamber, a stem on said valve extending throughout said cylinder head into said oil chamber, said stem being provided with a longitudinal conduit extending throughout its length, a ball valve disposed in the last mentioned conduit so as to allow air to flow outwardly toward said receiver and to prevent oil from flowing into said cylinder, and a spring for applying said mushroom valve on its seat, whereby said spring is flattened when the pressure in the receiver exceeds a predetermined value, so that the top of the cylinder is then directly connected to

the air chamber and the compressor ceases to force air into the receiver.

10. A fluid compressor of the type described, comprising in combination, a casing, a vertical cylinder in said casing, a piston adapted to reciprocate in said cylinder, a chamber in said casing located below said cylinder and in line therewith, two vertical parallel guiding plates in said chamber placed at a distance from each other substantially greater than the stroke of the piston, a cross head frame member rigidly connected to said piston and adapted to slide between said guiding plates, a crank pin for operating said cross head, a bushing surrounding said crank pin and adapted to slide transversely in said cross head, said cylinder being provided with ports connected with said chamber and opening into said cylinder at points level with the top of said piston when the latter is at the bottom of its stroke, means for admitting air into said chamber during the upward stroke of said piston, a receiver for the compressed air and means for allowing air to flow from said cylinder into said receiver during the upward stroke of said piston.

11. A fluid compressor according to claim 10 in which the lower part of said chamber is adapted to contain oil, further comprising a dipper integral with the lower part of said cross head adapted to splash said oil, whereby oil from said chamber is carried with the air into said cylinder, in order to eliminate dead space and to cool the head of the cylinder.

NICOLAS HERZMARK.
